(57) **CLAIM**

The ornamental design for a multi-person space hopper, as shown and described.

DESCRIPTION

FIG. 1 is a perspective view of a multi-person space hopper of the present invention;

FIG. 2 is a front view thereof;

FIG. 3 is a rear view thereof;

FIG. 4 is a top view thereof;

FIG. 5 is side view thereof, the opposing side view being a mirror image thereof; and,

FIG. 6 is a bottom view thereof.

The broken lines are included for the purpose of illustrating surface features that form no part of the claimed design.
